COMBINATION BABY WALKER AND HIGH CHAIR

Charles Starysky, Sheridan, Mont.

Application November 10, 1950, Serial No. 195,018

3 Claims. (Cl. 155—24)

1

My present invention relates to a combination supporting device for young children.

It is an object of my invention to provide a device which may be converted to many purposes such as, a walker, a chair, an amusement unit, and a stroller.

With the many uses of my invention, any mother's care and duties are minimized. For example, when a baby too young to walk alone is placed in the seat of the unit, he or she is protected from injury and may move around the home at will. Or, if the baby desires to be amused the seat is so mounted as to be rotatable like a merry-go-round. This rotatable feature also assists the baby in turning and moving in different directions to improve leg muscles and encourage use of the feet.

If it is the baby's feeding time the unit is readily convertible into a high chair with feeding tray and foot rest attachments. Or, if desired, after the baby has been fed, the device may be converted into a stroller for a walk outside the house.

Other objects, uses and advantages will become apparent as the invention is more fully described hereinafter in connection with the accompanying drawings.

In the drawings, wherein like symbols refer to like parts throughout the several views:

Figure 1 is a perspective view of my invention with the feed tray pulled apart for the sake of clarity.

Figure 2 is a cross section view taken along the section line 2—2 of Figure 1, but with the feed tray in mounted position.

Figure 3 is an enlarged cross section view of the mounting for the top rotatable ring which supports the seat portion of the unit.

Figure 4 is a fragmentary view in elevation of the unit showing a high chair leg attached, there preferably being three such legs used.

Figure 5 is a cross section view of a bushing connected to the inner surface of the lower edge of the arm rest ring, said bushing being formed with a bearing flange and a knee guard ring or flange.

Referring in detail to the drawing and first with particular reference to Figures 1 and 2, there is shown a frame work made of a plurality of superimposed vertically spaced flat surfaced rings, namely, 10, 11 and 12. Each ring is of a different size, that is, ring 10 at the base of the unit is the largest, ring 11 is the middle ring and is of smaller size than said ring 10 and ring 12 is the top ring and of the smallest size of

2

all three said rings. Thus, when the rings are secured together in their superimposed vertically spaced relation by the slanting brace bars 13, which extend through openings in the rings 10 and 11 to a bracket 14 secured by screws 15 on the inside of top ring 12, there is provided a pyramidal frame structure, see Figure 3.

The relatively large base ring 10 has an exterior rubber bumper 16 and is formed on its flat underside with sockets for the reception of the shanks of casters 17. The casters 17 are interchangeable with larger sized casters, not shown, for outdoor use, that is, when the unit is to serve as a baby stroller. Also, the base ring 10 is projected through at spaced intervals by rivets, such as 18 for telescopic insertion into the open end of tubular legs 19, see Figure 4. Thus, when a leg is engaged over the end of a rivet 18 projecting from the lower flat surface of the base ring 10, there is provided a high chair.

The middle ring 11 may serve as a climbing rung for the baby to get into the seat 19. The seat is mounted for rotation with an arm rest ring 20, provided with an annular slotted metal bushing 21 formed with a bearing flange 22 and a knee guard 32. The bushing is secured to the lower portion of the interior surface of the lower part of the ring 20. Seat 19 is secured by an elongated bolt 23 and a sheet metal back rest 24 to the lower edge and inner surface, respectively, of the ring 20.

The arm rest ring 20 is formed with an annular top flange 25 around its top edge overlapping the inner peripheral surface of the top frame ring 12 in which the rest ring 20 is concentrically positioned. The upper side of flange 22 of bushing 21 extends outwardly under the edge of the ring 20. The underside of the flange 22 serves as a bearing surface adapted to turn or rotate on resiliently yieldably mounted ball bearings 26. As shown, these ball bearings 26 are yieldably and adjustably mounted in cups 30 mounted on brackets 27, which brackets are of resiliently yieldable metal, see Figure 3. These brackets are angle brackets and are secured to the upper inner sides of the angular brace bars 13 by suitable means such as screws 28. Thus, as the flange 25 of the arm rest ring 20 is slightly elevated or spaced from the surface of the top ring and the seat 19 is secured to ring 20 which carries bushing 21 and flange 22, it follows that the weight of an occupant of the seat forces the bearing flange 22 downward tightly against the spring mounted ball bearings 26, which yield in their respective cup mountings and brackets to cushion the seat for vertical movements. Also each end of each

ball bearing bracket 27 is formed with a threaded aperture for the threaded shank 29 of the ball bearing socket or cup 30. Thus turning of the shank 29 serves to adjust the vertical position of the bearing cups 30. A nut 31 threads over the shank 29 and holds the same in adjusted position, see Figure 3.

The occupant's knees must be protected from the bearing brackets 27 and accordingly, the flat guard ring or flange 32 forming a part of the bushing 21 extends across and below the brackets for this purpose.

Obviously, when a child is seated in the unit, the waist and upper part of the body below the shoulders are below the top ring 12 and arm rest ring 20 and it is preferable to provide an adjustable body conforming elastic belt or strap 33 to give the child a feeling of a greater security when using the same and center the child in the frame structure. For example, such strap 33 may be separable by a snap fastener 34, see Figure 1, and formed with intermediate adjustable loops 35 looped over hooked ended bolts 36 depending from the rotatable arm rest ring 20 on the inside of bushing 21 opposite the slots therein. The several loops 35 of the strap are adjustable for length and extend through the slots formed in the bushing 21 and similar slots formed in a rubber liner or skirt 37 also secured to the rotatable arm rest ring 20 by screws 38 or the like. Thus, a child in the seat is protected against possible injury from any part of the unit.

The arm rest ring 20 besides mounting the seat 19 mounts a feed tray 40, see Figures 1 and 2. The tray is formed with an arcuate edge 41 to conform to the interior bore of the ring 20, and the flange 25 has its rim formed with a socket 42 to receive a pin 43 extending from a block 44 with an arcuate edge adapted to conform to the exterior curve of the flange rim 25.

When the feed tray is to be used, it is preferable to lock the seat against turning. Accordingly, means are provided for this purpose. Such means consists of a lock pin 45 adapted to project through aligned openings in the rotatable flange 25 and the relatively fixed top ring 12. The lock pin 45 may be tethered to the unit by a chain 46 or the like. Usually when feeding the child it will be best accomplished by attaching the high chair legs 19a to their respective rivets 18 as shown in Figure 4. Also a foot rest panel 47 may be mounted on the base ring 10 by securing it with means 48. The foot rest is preferably sector-shaped and fits around the base of one of the angle braces 13. Further means in the form of nuts and bolts 49 are provided for tightly securing the foot rest in place.

The unit may be made in attractive colors and the headed bolts 50 around the exterior peripheral rim of top ring 12 serve to hang a skirt 60 or curtain 51 with hanger rings 52.

Without further description, it is believed that the foregoing amply describes the present novel arrangement and combination of parts which make up the structure of the present invention, and it is to be expressly understood that various changes now likely to occur to others may be made without departing from the scope of this invention. Reference should be had to the appended claims to determine the scope of my invention.

I claim:

1. A device for children, comprising a pyramidal frame formed of vertically spaced apart rings, said rings including a large size base ring, a middle

size middle ring and small size top ring, angular vertically extending brace bars connecting the rings together, an arm rest ring concentrically supported within said top ring, a bearing flange 5 carried by the arm rest ring, a seat rigidly suspended from said flange, angular vertically adjustable bearing brackets secured to the inner top sides of each of said brace bars, a bearing mounted in each of said brackets supporting the arm rest ring by engagement with the underside of said bearing flange, a guard member secured to the seat mounting below the bearing brackets, a protective tubular lining secured to the inner bore of the arm rest ring extending toward the said seat, an adjustable elastic body strap for centering an undersize child in the center of the arm rest, and caster supporting means for said pyramidal frame with respect to the floor or the like.

2. A device for teaching children to walk comprising a frame of vertically spaced rings, said rings including a base ring and a relatively smaller top ring, angularly extending brace bars connecting the rings together to form a rigid pyramidal structure, a flanged annular assembly concentrically within the top ring and held in suspension by inverted ball bearing supports, said supports being angularly vertically adjustable with the ball bearings thereof in contact with a flanged part of said annular assembly, a seat rigidly connected to said annular assembly, to thereby be turnable therewith in said top ring, a lock pin engageable through a part of said annular assembly and said top ring to thereby fix said seat against rotation for feeding a child in the seat, and supplementary legs for raising the height of the seat during such feeding.

3. A frame of pyramidal form, comprising, a plurality of vertically spaced apart rings of progressively smaller sizes, brace bars secured to the rings to hold the same together, a seat, said seat having an annular rotatable arm rest positioned concentrically in the top ring of the frame, an annular rotatable part connected to said annular arm rest, an exterior annular flange carried by said rotatable part and positioned below the plane of said arm rest, said arm rest being connected as a unit to said rotatable part with said exterior flange, rigid connecting rods having an end connected to said seat and their respective opposite ends anchored to and depending with the seat from said exterior flange, and bearing units fixed to the frame brace bars and supporting the said annular part and the said seat by contact with the underside of said flange.

CHARLES STARYSKY.
